CLAIM

The ornamental design for an infant walking trainer, as shown and described.

DESCRIPTION

FIG. 1 is a front elevational view of an infant walking trainer showing my new design;

FIG. 2 is a rear elevational view thereof;

FIG. 3 is a top plan view thereof;

FIG. 4 is a bottom plan view thereof;

FIG. 5 is a right side elevational view thereof, the left side being a mirror image of the right side shown therein; and

FIG. 6 is a perspective view thereof in collapsed condition and on a reduced scale.
